UNITED STATES PATENT OFFICE.

SAMUEL B. STINE AND JAMES V. SMITH, OF OSCEOLA MILLS, PENNSYLVANIA,
ASSIGNORS TO THE STINE-SMITH MACHINE CO., OF SAME PLACE.

COAL-MINING MACHINE.

SPECIFICATION forming part of Letters Patent No. 443,925, dated December 30, 1890.

Application filed September 6, 1886. Serial No. 212,779. (No model.)

To all whom it may concern:

Be it known that we, SAMUEL B. STINE and JAMES V. SMITH, of Osceola Mills, in the county of Clearfield and State of Pennsylvania, have 5 invented a new and useful Improvement in Coal-Mining Machines; and we do hereby declare the following to be a full, clear, and exact description thereof.

Our invention relates to mining machines 10 employed in undercutting the vein of coal in coal-mines, and has special reference to that general class of coal-mining machines shown in Letters Patent No. 343,346, granted to us June 8, 1886, its object being to simplify the 15 construction of these machines and add to their efficiency for work, as hereinafter set forth. In the mining machine shown in said Letters Patent objections were found to the operation of certain parts, the principal objection being that the driving-chains could 20 not be drawn so tight as to prevent a slight swaying of the chains, and the knives or cutters thereon were thus thrown against the walls of the kerf or under-cut and frequently 25 subjected to sufficient strain to break them off. In that and other like mining-machines complicated gearing has been employed to transmit power from the engine-shaft to the driving-chains, and in the mechanism for feeding and withdrawing the traveling carriage at 30 the forward end of which the cutter-bar was mounted, and the cost of the machine was increased thereby, while great loss of power was occasioned by friction and the parts could not 35 be made as heavy as desirable and were more liable to breakage under the severe strains to which the machine was subjected. By our improvements these objections are substantially overcome.

40 In our improved mining-machine we have combined with the traveling carriage having the rotary cutter-bar mounted at the forward end a chain-shaft mounted in the carriage back of the cutter-bar and driven by an endless chain and a short driving-chain mounted 45 on said chain-shaft and cutter-bar and carrying knives or cutters to cut a course for the chain in the coal, the chain carrying the cutters being so short that all liability of the 50 swaying thereof and the breaking of the cutters is overcome. We have also mounted the

engines on an incline and connected the engine or crank shaft directly to the driving-shaft by suitable gearing, and we have operated the feeding mechanism from the driving-shaft and the receding mechanism from the engine-shaft, thereby dispensing with both the intermediate shaft and the recede shaft, and so simplifying the power mechanism of the machine. We have also mounted the 55 worm-rack, with which the feeding and receding mechanism engages, on the stationary bed under the feeding and receding mechanism, so dispensing with the two worm-racks and double sets of such mechanism engaging 60 therewith. We have also improved the construction of the clutch mechanism.

To enable others skilled in the art to make and use our invention, we will describe the same more fully, referring to the accompanying 70 drawings, in which—

Figure 1 is a top or plan view of our improved mining-machine. Fig. 2 is a side view of the same. Fig. 3 is a longitudinal section on the line $x-x$, Fig. 1. Fig. 4 is a longitudinal 75 section of the cutter-bar and chain-shaft on the line $y-y$, Fig. 1; and Fig. 5 is a view of the mechanism for operating the clutch.

Like letters of reference indicate like parts in each figure.

The stationary bed A is formed of the two side portions a , secured together by the rear housing a' and the cross-braces a^2 , the bed being mounted on runners a^4 to provide for the moving of the machine within the mine, 85 the runners supporting the bed the proper distance above the mine-floor, and the rear housing a' extending across between the side portions a back of the course of the traveling carriage B, while the cross-braces a^2 of 90 the bed extend across from the runners a^4 close to the floor, so leaving space between the side portions a for the movement of the operative parts of the traveling carriage, and so enabling the engines and operative mechanism to be lowered between the side portions of the bed. Supported longitudinally 95 on the cross-braces a^2 of the bed is the worm-rack a^3 , with which the feeding mechanism engages to feed and recede the carriage, as 100 hereinafter described. The traveling carriage B is mounted in said stationary bed, as

fully described in said Letters Patent No. 343,346, the carriage being formed of the side bars *b*, connected at the rear by the bed-plate *c*, supporting the power apparatus, and in 5 front of the bed-plate by the cross-brace *b'* and diagonal bars *b*². The bed-plate *c* is bolted to the side bars *b* by means of bolts *c'*, passing through slots or elongated bolt-holes *c*², so permitting the longitudinal adjustment 10 of the bed-plate on the carriage, as herein-after described, screw - bolts *c*³, passing through lugs *c*⁴ on the side bars *b* against the front edges of the bed-plate to arrange for an exact adjustment thereof on the carriage. 15 Bolted to the side bars *b* or bed-plate *c* are the engine standards or frames *e*, at the rear ends of which are the engine-cylinders *E*, having the valve-chests *d* on their innersides, the air-supply pipe *d'* communicating with 20 the valve-chests, and air being admitted thereto through the valve *d*³ in the pipe *d'*. The valves are operated by eccentrics *d*⁴ on the crank-shaft. The crank-shaft *f* is journaled in bearings *f'* on the bed-plate in front 25 of the standards *e*, the cranks *f*² being secured thereto beyond the carriage, and the standards having the guides *e'* for the slides *e*² of the pistons *e*³, which are connected to the cranks by the pitmen *e*⁴. Journaled in 30 the bearings *g'* on the bed-plate *c* is the driving-shaft *g*, the ends of which extend through openings in the standards *e* (shown in dotted lines) beyond the carriage to receive the sprockets for the outer driving-chains, the 35 crank-shaft and driving-shaft being the only cross-shafts on the bed-plate.

Power is communicated from the crank-shaft to the driving-shaft through the gear-wheels *h* *h'*, the gear-wheel *h* on the driving-shaft being made sufficiently large relatively 40 to the gear-wheel *h* to reduce the speed and increase the power necessary to drive the cutter-bar at the required speed and without the interposition of any intermediate gearing, 45 and the friction of such gearing and the shaft supporting the same being done away with. As hereinafter described, the carriage is fed forward and withdrawn by mechanism operated directly from these shafts *f* *g*, and for 50 this reason they are placed close to the bed-plate, and to apply the power from the engine to the crank-shaft *f* without interfering with the driving-shaft *g* the engines are mounted on an incline, as shown, the slides 55 *e'* on the engine-frames *e* being placed above the driving-shaft *g* and inclined correspondingly to the engine-cylinder, as fully shown in Fig. 2.

Mounted in bearings *k*² *k*³, secured to the 60 cross-brace *b'* and bed *c*, respectively, is the longitudinal shaft *k*, carrying at its forward end the worm-wheel *k'*, which meshes with the worm-rack *a*³ on the stationary frame *A*, and through which the traveling carriage is 65 fed forward and back in operating the machine. The carriage is fed forward by means of the worm-wheel *i* on the driving-shaft *g*,

which meshes with the worm-gear *i'* running loosely on the shaft *k* and engaging therewith through the clutch *m* keyed to said shaft, 70 and the carriage is fed backward or withdrawn by means of the worm-wheel *l* on the crank-shaft *f*, meshing with the worm-gear *l'* running loosely on the shaft *k* and engaging therewith through the clutch *m*. The speed 75 of the driving-shaft is about one-fourth that of the crank-shaft and the feed of the worm-gearing *i* *i'* is very slow, as it is made single-threaded, with but slight pitch, so that a slow 80 feed of great power is obtained, while the worm-gearing *l* *l'* is operated from the fast-running crank-shaft, and is made double-threaded and of more than double the pitch of the worm-gearing *i* *i'*, and all necessary speed for receding the machine is obtained. By 85 placing this feed and recede gearing in the center of the machine and supporting the worm-rack on the cross-braces of the stationary bed and under the feeding mechanism, we dispense with the double set of such mechanism and worm-racks, so simplifying the feeding mechanism, and we also apply the power 90 in such position as to obtain more direct action of the parts.

The clutch *m* is operated by means of the 95 sliding rack-bar *m'*, mounted in suitable guides and having fingers *m*² fitting in the annular seat *m*³ in the clutch *m*. A pinion *n* on the lower end of the vertical bar *n'* engages with the rack-face on the bar *m'*, the said bar *n'* having a handle *n*², by means of which, through the pinion *n* and rack-bar *m'*, the clutch can be thrown into and out of engagement with either worm-gear *l'* or *i'*, according to the desired movement of the carriage *B*. By these devices the clutch-lever can be located at the rear of the carriage in a more convenient position for its operation by the workman. To stop the carriage on its backward or recede movement, the clutch-bar 100 *n'* is provided with the lever *n*³, which, when the clutch engages with the recede worm-gear *l'*, extends back of the bar *n'* in such position that when the carriage reaches the rear of the stationary bed it strikes against the stop or 105 arm *n*⁵, secured to the stationary bed, and is by it pressed forward, so turning the clutch-bar *n'*, and through the pinion *n* and rack-bar *m'* drawing the clutch *m* out of engagement with the worm-gear *l'*, and so stopping 110 the backward movement of the machine. In order to stop the machine in its forward movement, a similar stop or arm *n*⁶ is secured to the stationary frame at a suitable point to operate the lever *n*³, when the traveling carriage is advanced the full distance into the coal, the lever *n*³ then striking against the stop *n*⁶ and drawing the clutch out of engagement with the worm-gear *i'*, and so stopping 115 the machine in case the operator neglects to 120 operate the clutch-lever to reverse the machine. The clutch-bar *n'* is supported at its upper end by the bracket *n*⁴, secured to one 125 of the valve-cases. The bed-plate *c* is cut

away, as shown, to receive the several parts of the driving and feed gearing, and it is reinforced at c^3 , where the driving-gear fits into it, in order to add to the strength of the plate 5 where it is reduced in width.

The rotary cutter-bar p is journaled in bearings p' at the forward end of the machine, and the driving-shaft g transmits power to the rotary cutter-bar through the medium of 10 chains, a chain-shaft r being journaled at the forward end of the carriage just back of the cutter-bar p , and the rotary motion of the driving-shaft g being first communicated to the chain-shaft and thence to the cutter-bar. 15 The driving-shaft is provided with sprockets s , one within the carriage and one at each end of the shaft, where it extends beyond the carriage, and the chain-shaft r has corresponding sprockets r' , the driving-chains $S S'$ 20 passing over these sprockets and the driving-chain S within the carriage passing above and below the engine-shaft f , and the outside chains S' being mounted on the shafts $g r$ beyond the cranks of said shafts, so that there 25 is no interference between them.

Rotary motion is imparted to the cutter-bar p from the chain-shaft r by the endless chain t passing over the sprocket r^2 on the chain-shaft and the sprocket p^2 on the cutter-bar, the driving-shaft thus acting to rotate 30 the cutter-bar through the endless chains $S S'$, the chain-shaft, and the endless chain t . In order to cut a course or path for the endless chain t , we employ the knives or cutters 35 u on said chain, as fully shown in Fig. 4, this short chain carrying the cutters instead of providing the main driving-chains $S S'$ therewith, and the ordinary cutters v on the cutter-bar cutting out a path into which the 40 main driving-chains $S S'$ enter. By so constructing the cutting apparatus we are enabled to employ a short cutter-chain instead of the long chains described in the patent above referred to, and this short cutter-chain 45 can be so mounted on the chain-shaft and cutter-bar that there is practically no swaying movement therein, and hence there is no liability of any one of the cutters striking 50 against the coal in such manner as to subject it to such severe strain as to cause its fracture. The short chain also requires but few cutters, and for this reason the labor of sharpening and repairing the cutters is reduced.

At w is shown the ordinary jack to engage 55 with the face of the coal and support the stationary bed during the cutting operation, a similar jack being employed at the rear of the bed.

When the machine is in operation, after the 60 stationary bed has been secured in place, air is admitted to the engines and the rotary motion imparted to the cutter-bar through the cog-gearing $h h'$, driving-shaft g , chains $S S'$, chain-shaft r , and cutter-shaft t . The clutch 65 m is then caused to engage with the worm-gear i' , and through the worm i on the driving-shaft, worm-gear i' , shaft k , worm-gear k' ,

and worm-rack a^4 under the feed-gearing the carriage is then fed forward, the cutter-bar entering and undercutting the coal. The cutters u on the chain t cut a path in the coal for the chain, the cutters v on the bar cutting a path for the rest of the carriage which enters under the coal, and the coal-dust is carried back by the driving-chains $S S'$, which act to clear 70 the course for the carriage as well as drive the cutter-bar. As soon as the carriage is advanced the full distance into the coal the clutch is withdrawn from the worm-gear i' and caused to engage with the worm-gear l' , 75 and through the worm l on the crank-shaft and worm-gear l' the shaft k is turned in the opposite direction at a much higher speed and acts through the worm k' and worm-rack a^4 to rapidly withdraw the carriage. In case 80 the operator neglects to operate the clutch-lever either in making the cut or withdrawing the traveling carriage as the lever n^3 during the forward movement of the carriage strikes against the stop n^6 by turning the 85 clutch-bar n' through the pinion n and sliding rack m' it draws the clutch from engagement with the worm-gear i' , thus throwing the feed out of gear and stopping the forward movement of the machine, and, in receding, as 90 the carriage approaches the rear portion of the stationary bed-frame the lever n^3 comes in contact with the stop n^5 and through the same mechanism draws the clutch from engagement with the worm-gear l' , thus throwing 95 the machine out of gear and stopping the backward movement of the machine. The machine can then be shifted into position for 100 the next cut and the operation repeated.

By our improvements the operative mechanism is much simplified and friction of the parts and the power necessary to operate the machine greatly reduced, while at the same time heavier and stronger gearing may be employed without increasing the weight and 105 height of the machine, which is very important in this class of machinery, which is operated in mines and is necessarily shifted from point to point therein. The employment 110 of the short cutter-chain also reduces breakage of cutters to a minimum and reduces the 115 power necessary to operate the machine.

What we claim as our invention, and desire to secure by Letters Patent, is—

1. In a mining-machine, the combination of 120 a traveling carriage having a cutter-bar and a chain-shaft mounted at its forward end and a short chain passing around said cutter-bar and chain-shaft and driving the cutter-bar from the chain-shaft, substantially as and for 125 the purposes set forth.

2. In a mining-machine, the combination of 130 a traveling carriage having a cutter-bar and a chain-shaft mounted at its forward end, a short chain passing around said cutter-bar and chain-shaft and driving the cutter-bar from the chain-shaft, and cutters on the chain to cut a path therefor in the coal, substantially as set forth.

3. In a mining-machine, the combination of a traveling carriage having a cutter-bar mounted at its forward end, a chain-shaft mounted back of said cutter-bar, a chain or chains driving said shaft, and a short chain carrying cutters driving the cutter-bar from the chain-shaft, substantially as and for the purposes set forth.
4. In a mining-machine, the combination, with the stationary bed A, of the traveling carriage B, moving longitudinally thereon and carrying the cutter-bar at the forward end, the engine-standards e, supporting the engines in an inclined position, the crank-shaft f, mounted in front of the standards e and in journals on the bed-plate and carrying the gear-wheel h, the driving-shaft mounted in journals on the bed-plate back of the crank-shaft and carrying the gear-wheel h, and the driving chain or chains driving the cutter-bar from said driving-shaft and passing above and below the crank-shaft substantially as and for the purposes set forth.
5. In a mining-machine, the combination of the crank-shaft carrying the gear-wheel h and recede-worm l, the driving-shaft carrying the gear-wheel h', meshing with the gear-wheel h and the feed-worm i', driving chain or chains, and feeding and receding apparatus operated by said worms, substantially as and for the purposes set forth.
6. In mining-machines, the combination of the stationary bed having the cross-braces a², the worm-rack a⁴, secured to said braces, and the feeding and receding gearing located above said rack and formed of the recede-worm l, feed-worm i, longitudinal shaft k, worm-gears l' i' thereon, clutch m, and worm k' on the shaft k, meshing in the worm-rack, substantially as and for the purposes set forth.
7. In mining-machines, the combination,

with the stationary bed and the traveling carriage carrying feed and recede mechanism, of the clutch engaging therewith, the clutch-bar 45 carrying the lever n³, and the stops n⁵ n⁶ on the stationary frame acting to engage with the lever n³ and operate the clutch, substantially as and for the purposes set forth.

8. In a mining-machine, the combination of 50 the following elements, namely: a bed, a carriage traveling thereon and carrying the cutting apparatus, the engines mounted directly upon the carriage, the crank-shaft on the carriage between the engines and cutter-bar, the 55 mechanism for advancing the carriage and receding it, said mechanism having a revolving thread on the carriage, and having a threaded bar on the bed to engage with the revolving thread, and power-transmitting devices between the crank-shaft and the said revolving thread, substantially as set forth.

9. In a mining-machine, the combination of 60 the following elements, namely: a bed, a carriage traveling thereon and carrying the cutting apparatus, the engines on the carriage, the crank-shaft situated between the engines and the cutter-bar, carriage-moving mechanism having a threaded bar secured to the bed, and having a revolving thread on the carriage, a continuously-moving worm and worm 65 wheel to advance the carriage, and continuously-moving devices between the crank-shaft and the revolving thread for withdrawing the carriage, substantially as described. 70

In testimony whereof we, the said SAMUEL B. STINE and JAMES V. SMITH, have hereunto set our hands.
